AUTOMATIC DEMODULATOR SENSITIVITY
CONTROL

Rudolf Urtel and Karl Steimel, Berlin, Germany,
assignors to Telefunken Gesellschaft für
Drahtlose Telegraphie m. b. H., Berlin, Ger-
many, a corporation of Germany

Application October 21, 1933, Serial No. 694,666
In Germany December 22, 1932

6 Claims. (Cl. 250—27)

The present invention relates to demodulation circuit arrangements comprising means to insure automatic dependence of sensitiveness upon signal strength.

Automatic compensation of volume variations due to fluctuations in the incoming signal strength, say due to fading, may be effected by that, by the aid of suitable devices, the amplification factor or gain of the radio frequency amplifier below the demodulator is regulated in dependence upon the carrier-wave amplitude. Arrangements, however, have also been disclosed in the earlier art in which the sensitivity of the demodulator itself is regulated as a function of the carrier amplitude. Arrangements of this sort are predicated upon the use of special plate current-grid voltage or plate current-plate-potential characteristics according to the rectifier method that is in use. These characteristics result in a certain "Klirr" (distortion) factor, and as a general rule they permit of a sufficiently accurate compensation only inside relatively small fluctuations.

Now, according to the present invention, a novel arrangement is suggested which is designed to obviate these drawbacks, as follows:

In a three-grid tube whose first grid, figured from the cathode, serves and acts as the control grid, whose second grid serves as a screen-grid, and in which the third grid mounted between the said screen grid and the anode, or plate, is maintained at zero potential or at a negative potential in reference to the cathode, the slope (mutual conductance) being the ratio: Plate current variation to control-grid potential-variation is changeable by the adjustment of the voltage of the auxiliary grid.

Certain secondary actions of a troublesome nature such as decreasing internal resistance with increasing negative auxiliary-grid voltage can be obviated by the introduction of a second screen grid between auxiliary grid and anode. However, so far as the principle here described is concerned, these phenomena are immaterial.

In the drawing:—

Figures 1, 2 and 3 show different embodiments of the invention.

Now, if a tube of this kind is operated in a grid rectification circuit scheme (audion), as shown in Fig. 1, an audio component will arise at the control grid G_1 which is amplified by the electrode system in the usual way. A change in sensitivity is effected by that the D. C. component arising across the grid resistance R_g of the control grid 55 is wholly, or partly, impressed upon the auxil-

iary grid G_3 which varies the slope of the control grid. As the carrier-wave amplitude grows, there occurs a rise both of the audio amplitude at the control grid as well as the D. C. voltage component. The consequence of this is a decrease or loss in slope of the control grid, so that, if dimensions have been chosen properly, the audio output voltage can be kept practically constant. 5

The identical principle is applicable, with but slight changes, if rectification is effected in a separate rectifier, or rectifier path (diode, crystal detector, etc.) as shown in Fig. 2. The rectifier arrangement D again furnishes an audio component as well as a D. C. voltage component, the former one being impressed upon the control grid G_1 and the latter one upon the auxiliary grid G_3 regulating the slope of the control grid. 10

When using the basic idea of this invention in connection with a plate rectification circuit arrangement (Fig. 3), the operation would be thus: The control grid G_1 is given a negative biasing voltage $E'g$ so that the working point comes to lie in the lower bend of the characteristic curve and that plate rectification is insured. In the plate circuit is inserted a resistance R immediately at the cathode; the fall of potential occasioned across the said resistance serves as a biasing voltage for the auxiliary grid changing the slope of the control grid. As the carrier-wave 20 amplitude grows, there also occurs a rise in the plate D. C., the voltage drop across the cathode resistance increases, and the slope of the control grid is diminished by the influence of the auxiliary grid potential shifted into the negative 25 region, so that, if dimensions have been properly chosen, stabilization of the audio output amplitude is possible. 30

What is claimed is:—

1. In combination with a source of signals to be demodulated and a network for utilizing the audio component of the demodulated signals, an electron discharge tube provided with a cathode, a plate, a control grid adjacent the cathode, an auxiliary grid adjacent the plate, and a positive 40 screen grid between the two grids, a second network, including a signal input circuit, coupled between said source and the cathode and control grid of said tube, means in said second network for developing from said signals, between said 45 cathode and control grid, audio and direct current voltage components, and a direct current connection between the auxiliary grid and a direct current voltage point on said last means which is negative with respect to the cathode of 50 55

the tube whereby the said direct current voltage component is applied to said auxiliary grid as a gain regulation voltage for the tube, and said audio component being repeated into the plate circuit of the tube.

5 2. In a system as defined in claim 1, said direct current connection including a resistor.

3. In a system as defined in claim 1, said direct 10 current connection including a resistor connected between the control and auxiliary grids, and a second series resistor connected between the cathode and control grid, said two resistors being shunted by a condenser.*

4. In a system as defined in claim 1, said second 15 network means comprising a rectifier, and said control grid and cathode being coupled to the rectifier.

5. In combination with a signal demodulation 20 diode, a source of signals coupled to the diode, a tube having a cathode, a plate, and three grids between them, the diode being coupled between one of the grids and the cathode to impress the audio component of demodulated signals there-between, a direct current connection between the diode anode and a second of the grids, the diode

cathode and said tube cathode being at the same direct current potential, and a third of the grids being disposed between the first and second grids and being at a positive potential with respect thereto.

5

6. In combination with an input network of electrical waves, an electron discharge tube of the type including a cathode, a plate, a signal control grid adjacent the cathode, a gain control electrode adjacent the plate, and a positive screen 10 electrode between the control grid and gain control electrode, a signal utilization network coupled to the plate and cathode, said input network being coupled between the cathode and control grid, means, including a resistor having one 15 side thereof connected to said cathode, for deriving from said waves a direct current voltage whose value varies with the wave amplitude, and a direct current connection between the gain control electrode and the other side of said resistor where the potential of the gain control electrode with respect to the said cathode is a function of said wave amplitude.
